Patented Jan. 6, 1920.

UNITED STATES PATENT OFFICE.

WILLIAM L. PAUL, OF BERKELEY, CALIFORNIA, ASSIGNOR TO DEERE AND COMPANY,
OF MOLINE, ILLINOIS, A CORPORATION OF ILLINOIS.

CULTIVATOR.

1,327,212.

Specification of Letters Patent.

Patented Jan. 6, 1920.

Application filed April 25, 1916. Serial No. 93,403.

To all whom it may concern:

Be it known that I, WILLIAM L. PAUL, a citizen of the United States, residing at Berkeley, in the county of Alameda and State of California, have invented certain new and useful Improvements in Cultivators, of which the following is a specification, reference being had therein to the accompanying drawing.

10 My invention relates to cultivators and more particularly to the mechanism employed to raise and lower the gangs and to control the depth of cultivators, and the object of my invention is to simplify and at 15 the same time increase the efficiency of such mechanism.

Referring to the drawings in which similar numerals indicate identical parts—

20 Figure 1 is a side elevation of part of a cultivator, with the wheels removed, illustrating the application of my invention.

Figs. 2 and 3 are detail views.

25 To a frame 1, I rigidly secure a draft pole 2; depending from the frame 1 is an arch 3 on the lower ends of which are journaled, and adapted for vertical movement, the forward ends of gang beams 4 carrying standards 5 to which are secured suitable earth working devices 6, in this instance shovels, 30 but disks or other types may be used. As shown and described Fig. 1 of the drawings, being an elevation shows but one side of the cultivator, on the opposite side however, similar parts are carried, the following description 35 therefore will apply to both sides of the cultivator. The gang beam 4 is of the usual well known type of two connected beams spaced apart and connected together. A brace 7 is secured to the lower end of 40 the support 3 and to the forward part of the frame 1; a similar brace 8 is secured to the lower end of the support 3 and extends upwardly and rearwardly to the rear of the frame 1 where it is secured.

45 Rigidly secured on the frame 1 is a rearwardly projecting segment 9 having notches 10. Pivotedly supported on the rear of the frame 1 is a hand lever 11 provided with the usual type of latch to engage with the 50 notches in the segment 10. Preferably integral with the lever 11 and extending forwardly therefrom is an arm 12 having pivotally connected to its forward end a rod 13 which projects downwardly to a bracket

14 secured on the gang beam 4; the bracket 55 14 is provided with a perforation through which the rod 13 projects and is held in place by a pin or cotter 15 which is inserted in a suitable hole in the rod 13 below the bracket 14, the perforation in the bracket 60 14 being sufficiently large to permit the gang beam 4 to rise freely on the rod 13. Pivotedly connected to the forward end of the arm 12 is a rod 16 extending downwardly forward of the rod 13 and playing 65 freely through a perforation in a bracket 17 rigidly secured on the gang beam 4; a coil spring 18, on the rod 16 exerts its pressure against the bracket 17 and a pin 19 on the rod 16. 70

The coil spring 18 holds the cultivating gang, to the depth set, by pressure on the bracket 17 on the gang beam 4, the latter however can rise against the pressure, when an obstruction is encountered by the cultivating devices, the cotter 15 holding the gang beam 4 against downward movement except by operation of the lever 11 and the pressure of the coil spring 18; the coil spring 18 also assists in lifting the gang beam 4 80 when the lever 11 is actuated rearwardly to raise the gang beam 4 through the connection of the lever therewith by the rod 13 and the cotter 15 acting against the underside of the bracket 14. In the drawings is shown 85 in dotted lines the position of the raising mechanism and the gang beam when the latter is raised.

The operation of raising the gang beam is assisted by the spring 18 in the following 90 manner; the latch on the lever 11 having been released from the notch in which it was set, the lever 11 swung rearwardly and downwardly consequently the arm 12 moves upwardly, raising the gang beam 4 through 95 the connection of the rod 13 therewith and with the arm 12. When the gang beam 4 is down and the lever 11 locked in position as shown in full lines in Fig. 1, the spring 18 is contracted and exerts its tension between 100 the bracket 17 and the pin or cotter 19, holding the beam down against the cotter in the lower end of the rod 13, but as the arm 12 is shorter than the distance between the bracket 14 and the pivotal point 4^a of the 105 gang beam the arm 12 moves at a greater speed than the gang beam 4 in the operation of raising the latter, the spring 18 exerts its

expansive force in the direction of the faster moving arm 12 thus assisting in raising the latter and the beam 4 to which it is connected.

What I claim is—

- 5 1. In a cultivator, the combination of a frame, a gang beam pivotally supported on the frame, a lever pivoted on the frame and operable to raise and lower the gang beam and having an arm extending forwardly 10 from the pivot, a rod pivoted to the free end of said arm and extending downwardly to connection with the gang beam, a rod pivoted to the free end of said arm and having a sliding connection with the beam, and a 15 coil spring on said rod exerting its pressure to hold the gang beam down and coöperating with the lever to lift the beam.
2. In a cultivator, the combination of a frame, a gang beam pivotally supported on the frame, a lever pivoted on the frame and 20

having an arm extending therefrom, a rod pivoted to the free end of said arm and extending downwardly to connection with the gang beam whereby the latter is raised or lowered by operation of the lever, a second rod pivoted to the free end of said arm and having a sliding connection with the gang beam at a point intermediate the connection of the first mentioned rod with the beam and the pivotal connection of the beam with the frame, and a coil spring on said second rod, said spring acting to hold the beam down and coöperating with the lever to raise the beam. 25 30

In testimony whereof I affix my signature, 35 in presence of two witnesses.

WILLIAM L. PAUL.
